UNITED STATES PATENT OFFICE.

ALBERT H. CARRIER, OF ASHEVILLE, NORTH CAROLINA, ASSIGNOR OF ONE-HALF TO
EDWIN W. GROVE, OF ASHEVILLE, NORTH CAROLINA.

CASEMENT.

1,302,765.

Specification of Letters Patent.

Patented May 6, 1919.

Application filed August 9, 1916. Serial No. 113,921.

To all whom it may concern:

Be it known that I, ALBERT H. CARRIER, a citizen of the United States, residing at Asheville, in the county of Buncombe and 5 State of North Carolina, have invented new and useful Improvements in Casements, of which the following is a specification.

The present invention relates to improvements in casement mountings and the primary 10 objects of the invention are to provide an improved mounting for the sash and improved means for mechanically moving the sash into different desired positions, whereby the sash may be swung into open position 15 for ventilation, it may be swung into a position which will enable the sash to be cleaned easily and from the inside, and it may be swung into a position parallel to the wall of the building, or substantially so, and thus 20 avoid forming an obstruction at the outside of the building, all these movements of the sash being accomplished with facility and ease by the aid of the mechanical operating means for the sash, which operating means 25 may further serve to lock the sash in its closed or any other desired position.

A further object of the invention is to provide a casement wherein the sash is capable of the movements described and which 30 also embodies means for swinging or operating the sash mechanically, and yet the casement may be made at reasonable cost, installed in buildings without difficulty, and the sash mounting and operating parts are 35 inclosed or concealed so as to avoid forming obstructions, and the structure presents a neat appearance.

To these and other ends, the invention consists in certain improvements, and combinations and arrangements of parts, all as 40 will be hereinafter more fully described, the novel features being pointed out particularly in the claims at the end of the specification.

In the accompanying drawing:—

45 Figure 1 is an elevation of a casement constructed in accordance with the present invention, the same being viewed from the inner side.

Fig. 2 represents a vertical section through 50 the casement, the sash being shown in closed position.

Fig. 3 represents a horizontal section through the casement, the sash being shown in closed position by the full lines, in open 55 position for ventilation by the dotted lines,

in the position for cleaning by the dot-and-dash lines, and in position substantially parallel with the outer side of the building by the dash lines.

Fig. 4 is a detail view showing the fittings 60 which secure the sash to the swinging sash mountings.

Fig. 5 is a detail sectional view, on an enlarged scale, showing the sash operating means. 65

Fig. 6 is a detail view showing the operating crank in reversed position on the operating shaft, and

Figs. 7 and 8 are detail views showing the bearing for the operating worm, and the 70 related parts.

Similar parts are designated by the same reference characters in the several views.

Casements constructed in accordance with the present invention may be installed in 75 buildings of various kinds, it being understood that modifications and changes in the construction and arrangement of parts may be made to suit different requirements. The preferred embodiment of the invention is 80 shown in the accompanying drawing and will be hereinafter described in detail, although equivalent constructions are contemplated and will be included within the scope of the claims. 85

The casement, as shown, embodies a frame comprising vertical side rails 1 and 2, a top rail 3, and a bottom rail or sill 4. The top and side rails are formed with a rabbet 5 at the outer side of the frame, and a stool 6 90 is fitted on the top of the sill 4, the sash frame 7 being adapted to fit into the rabbet and against the outer edge of the stool to form a suitable weather-tight joint. The sash may be of any suitable construction and, 95 as shown, it is provided with a glass pane 8. In the present instance, the sash is pivoted at its right-hand side and the vertical rail 2 of the casement frame is provided with a rib 9 to engage the outer side of the sash 100 frame and thus provide a good weather-tight joint at this point.

According to the present invention, the sash is supported or carried by a pair of sash mountings 10 and 11. The upper 105 mounting 10 comprises a plate or bracket which is attached to the upper portion of the sash frame by a pivot pin 12 and is attached to the upper rail 3 of the casement frame by a pivot pin 13, the latter coöperating with 110

- a plate 14 which is fastened by screws or other suitable means to the under side of the top rail 3. The lower mounting 11 is likewise connected to the sash by a pivot 15 and it is connected to the sill or lower member of the casement frame by a pivot pin 16 which extends through a plate 17, the latter being secured by screws or equivalent means to the upper side of the sill.
- 10 Means is provided whereby the sash may be secured to the sash mountings so that the sash will swing in unison with the swinging movements of these sash mountings about the pivots 13 and 16, or the sash may swing 15 relatively to the sash mountings on the pivots 12 and 15. Preferably, and as shown, an arm 18 extends downwardly from the mounting 10 and a similar arm 19 extends upwardly from the mounting 11, these arms 20 being shaped or adapted to lie flatwise against the outer side of the sash frame when the latter is in position to swing with the sash mountings. Means coöperative with these arms serves to fasten the sash frame 25 to the swinging mountings. As shown, the arms 18 and 19 are provided with slots 20 and 21 and with recesses 22 and 23 extending crosswise of the slots, and bolts 24 and 25 are extended through the sash frame and 30 have heads 26 and 27 on their outer ends and thumb-nuts or equivalent tightening means 28 and 29 on their inner ends to co-operate with the inner side of the sash frame. By loosening the bolts and turning the heads 35 26 and 27 into alinement with the slots 20 and 21, the heads of the bolts may pass through the slots of the arms 18 and 19, and hence the sash frame may then be swung about its pivots 12 and 15. On the other 40 hand, when the sash frame is swung into a position to bring its outer side against the arms 18 and 19, the heads 26 and 27 of the bolts, after passing through the slots 20 and 21, may be turned, and after these heads 45 have been seated in the recesses 22 and 23, the thumb-nuts 28 and 29 may be tightened, thereby fastening the sash frame to the upper and lower sash mountings, and the sash will then swing in unison with the swinging 50 movements of these mountings about the pivots 13 and 16 as an axis. Ordinarily, the sash frame will be fastened to the sash mountings, swinging motion of the sash mountings in one direction about the pivots 55 13 and 16 as an axis bringing the sash into the closed position, as shown by the full lines in Fig. 3, while swinging motion of the sash mountings in an opposite direction about the same axis will swing the sash 60 either into the fully open position shown by the dotted lines in Fig. 3, or any desired intermediate position. When, however, the sash is unfastened from the arms 18 and 19 of the sash mountings, the sash may then be 65 swung about the pivots 12 and 15 of the sash

mountings as an axis. For example, the sash may be swung into the position shown by the dot-and-dash lines in Fig. 3, which position enables cleaning of the sash to be accomplished with facility and, also, the sash 70 may be swung into the position shown by the dash lines in Fig. 3, the sash then lying in a plane parallel to the wall of the building, or substantially so, and thus reducing to a minimum the obstructing action of the 75 sash at the outer side of the building. This latter adjustment of the sash is advantageous where the casement is fitted in the wall of a building which faces a porch.

The present invention provides simple and efficient means for operating the sash with facility and ease, thereby enabling the sash to be adjusted by feeble or infirm persons. Preferably, and as shown, the lower sash mounting 11 is formed with a gear sector 85 or quadrant 30 which is concentric with the pivot pin 16, and a worm 31 is provided which coöperates with the quadrant. The worm is fixed to an operating shaft 32, and a box 33 provides bearings 34 and 35 for 90 the shaft and also serves to substantially inclose the worm. The box may be made in two sections, as shown, to facilitate its manufacture and the assembling of the worm and shaft therein, and the box may be set in a 95 recess 36 formed in the upper side of the sill 4. In order to balance the weight of the sash and thus facilitate the movements thereof, a track 37 is formed on the sash mounting 11 at the outer side of the quadrant 30, this track being concentric with the axis 16, and a roller 38 is mounted in the box 33 and coöperates with the under side of the track, the roller and track sustaining substantially the weight of the sash and thus 100 relieving the pivots 13 and 16 of the strain and correspondingly diminishing friction incident to the swinging movements of the sash. The operating shaft 32 is extended inwardly through a channel or bore 39 105 formed in the top of the sill, and through a molding 40 such as is usually fitted to the inner side of the sill beneath the stool. Preferably, and as shown, an escutcheon 41 is fitted into the molding and serves as a 110 bearing to steady the inner end of the operating shaft. The inner end of the operating shaft preferably has a squared or angular end 42, and a crank 43 with a correspondingly shaped hub is removably fitted to this 115 squared or angular end of the operating shaft, the crank having an inwardly projecting handle 44. The quadrant and the operating shaft are covered and concealed by the stool 6, the lower side of the stool and 120 the upper side of the sill being appropriately recessed to provide pockets within which these parts may operate. By rotating the shaft 32 by manipulation of the crank 43, the worm 31 operates upon the quadrant 30 to 125 130

swing the sash about the pivots 13 and 16 as an axis. By this operation, the sash may be swung either into open or closed position, or any intermediate position. When, however, it is desired to clean the sash, the same is first swung to its fully open position, the bolts which fasten the sash to its mounting are unfastened, and the sash is then swung into substantially the position shown by the 10 dot-and-dash lines in Fig. 3, it being preferable, to facilitate cleaning, to operate the shaft 32 in the direction which closes the sash until the sash has been brought into the position shown by the dot-and-dash 15 lines in Fig. 3. The sash may be swung into the position shown by the dash lines in Fig. 3 by operating the shaft 32 in a direction to swing the sash into its fully open position, and by unfastening the sash from the 20 sash mountings, the sash may be swung into the position shown by the dash lines. Owing to the use of a worm and a gear segment for effecting the opening and closing movements of the sash, the operating shaft has 25 such a mechanical advantage over the sash that the sash may be swung into the desired position by the application of a relatively light force to the operating crank.

Preferably, and as shown, the crank is removable from the shaft and is capable of being applied in reverse position thereon. This is advantageous in that it removes the crank as an obstruction at the inner side of the casement, and by providing an opening 35 or bore 45 to receive the handle 44 of the crank when the latter is applied in reverse position on the shaft, the crank will lock the operating shaft from rotation and hence will act as a lock to retain the sash either in 40 closed position or in any other desired position.

A casement constructed in accordance with the present invention is not only capable of operation with ease and facility, but 45 it presents the further advantage that the sash may be operated without the necessity or removing or otherwise disturbing the window screen or shade when such are used.

I claim as my invention:—

50 1. A casement comprising a casing, a sash to fit therein, a pair of mountings pivotally supported on the casing and pivotally connected to the top and bottom edges respectively of the sash at points intermediate the width of the sash, each mounting having an arm arranged to engage the outer face of the sash, and devices to coöperate with said

arms and the sash to detachably secure them whereby the sash may swing in unison with said mountings and may also swing independently of said mountings. 60

2. A casement comprising a casing, a sash to fit therein, a pair of mountings pivotally supported on the casing and pivotally connected at the top and bottom edges respectively of the sash at points intermediate the width of the sash, each mounting having an arm arranged to engage the outer faces of the sash, and bolts extending through said arms and the adjacent portions of the sash 70 for detachably securing the sash to said mountings.

3. A casement comprising a casing, a sash to fit therein, a pair of mountings pivotally supported on the casing and pivotally connected to the top and bottom edges respectively of the sash at points intermediate the width of the sash, each mounting having an arm arranged to engage the outer face of the sash, each arm having a slot therein, and 80 bolts having T-heads adapted for insertion through the respective slots in said arms and operative to clamp the sash in fixed relation to said mountings.

4. A casement comprising a casing, a sash to fit therein, a pair of mountings pivotally supported in the casing and pivotally connected respectively to the top and bottom edges of the sash to permit swiveling of the sash relatively to such mountings, a gear 90 sector fixed to one of said mountings, and a worm journaled in the casing and coöoperative with said gear sector, said worm being operative from the inner side of the casing.

5. A casement comprising a casing, a sash to fit therein, a pair of mountings pivotally supported in the casing and pivotally connected respectively to the top and bottom edges of the sash, a gear sector fixed to one of said mountings, a worm shaft journaled 100 in the casing and having a worm thereon coöoperative with said gear sector, and an operating handle reversibly fitting the inner end of the worm shaft, the casing having a recess adjacent to said shaft to receive a 105 part of said handle to thereby lock the worm shaft.

In testimony whereof I have hereunto set my hand in presence of two subscribing witnesses.

ALBERT H. CARRIER.
